UNITED STATES PATENT OFFICE

PHILIP X. RICE, OF STAUNTON, VIRGINIA, ASSIGNOR TO GENERAL RAILWAY SIGNAL COMPANY, OF ROCHESTER, NEW YORK

TRAIN-CONTROL TRACK ELEMENT

Application filed May 23, 1929. Serial No. 365,391.

This invention relates in general to inductors as used in train control systems, and has more particular reference to an inductor for use in an intermittent inductive alternating current type of train control system, such as disclosed, for example, in the pending application of Philip X. Rice, Ser. No. 106,478 filed May 3, 1926, and in the application of W. H. Reichard, Serial No. 358,577, filed April 27, 1929, and entitled "Train control system."

Among the objects of this invention are to provide an improved inductor which is rugged and compact, simple in design, efficient and long lived in use, and cheap to manufacture.

It is a further object of this invention to provide an improved housing for the inductor for snugly receiving and shielding the inductor cores and coils, condensers, etc., so as to permit of effectually protecting all such parts from the weather.

Further objects, purposes and characteristic features of the invention will appear as the description progresses, reference being had to the accompanying drawings showing, solely by way of example, and in no manner in a limiting sense, one form which the invention can assume. In the drawings:

Fig. 1 is a plan view showing an inductor core and coil structure in detail, in accordance with this invention, and showing in a wholly diagrammatic manner the electrical connections associated therewith.

Fig. 2 is a plan view of an inductor per se, in accordance with this invention.

Fig. 3 is a side elevation, with parts broken away, of the inductor of Fig. 2.

Fig. 4 is a sectional view, to an enlarged scale, on line 4-4 of Fig. 3, viewed in the direction of the arrows.

Fig. 5 is a sectional view, with parts shown in elevation, and to an enlarged scale, on lines 5-5 of Fig. 3, viewed in the direction of the arrows.

Referring now to the drawings, and first to Fig. 1, there is here shown a stretch of track constituted by track rails 1 divided by insulating joints 2 into two signal blocks, each block having a source of electrical en-

ergy 3 connected across its exit end, and a track relay TR connected across its entrance end, traffic being in the direction of the arrow. Represented by wheels and axles 4 is a car on the stretch of track.

The core and coil structure of an inductor in accordance with this invention is shown in considerable detail in Fig. 1. For the sake of clearness, the core of the inductor is shown positioned to one side of the track rails, although in practice, it is placed between the track rails, as shown in above mentioned Reichard application. From this figure it is seen that the core C is in the general form of 8, with two loop portions having substantially parallel sides 5-6 and 7-8, with a neck 9 interconnecting the loop portions, and an extending arm 10 and 11 extending beyond the outer end of each loop portion.

A coil 12 is carried on the neck portion 9 of the core C and end coils 13 and 14 are carried, respectively, on the arms 10 and 11.

The coil 12 has a tuning condenser 18 connected across it, and is connected up in a series circuit including tuning condenser 15, contact finger and front point 16 of a line relay LR controlled by track relay TR and the track relay (not shown) for the block immediately in advance, and tuning inductance 17, whereby coil 12 is controlled by traffic conditions ahead either to choke or to not choke the intermediate portion of the inductor according as armature 16 is attracted or retracted, corresponding to clear, or caution and danger conditions, respectively. This control is the same as described in detail in the applications above referred to, and requires no further comment in this case.

The coils 13 and 14 are connected in series, together with a tuning condenser 19, by way of a jumper 20, so that they normally act to choke the ends of the inductor core regardless of traffic conditions, but can be subjected to traffic control by the removal of the jumper 20, whereby to place them under control of contact finger 21 and front point of relay TR, all as described in greater detail in the above referred to application of Reichard.

The core C is made up of a number of

stamped, or otherwise formed, laminations, which are piled together to make a substantially straight bar in vertical projection. The center part of this bar is then taped, as at 22, to hold the laminations together, after which coil 12 is wound thereon or is form wound and slipped thereon. Then the laminations on each side of the tape 22 are divided and separated, as shown in Fig. 1, and 5 a spacer 23 of wood or other material (Fig. 5), is inserted between the parallel arm 5-6 and 7-8 to hold the laminations in proper position. The ends of the two arms forming each loop are then brought together and taped 10 to constitute the extending arms 10 and 11, after which coils 13 and 14 are wound thereon or form wound and slipped thereon, as the case may be.

The above described method for forming 20 the core and coil structure of this invention has been found very saving of time and labor, and permits making a core structure of the shape shown without using an undue amount of transformer iron therein.

25 In order to widen the upper horizontal surfaces of the arms 5-6 and 7-8, overhanging core portions are used, constituted by, in each case, a plurality of Z shaped laminations 24, which are stacked as shown in Figs. 1 and 5, 30 and held in place, preferably, by means of the receiving casing for the core, to be described in detail below. The function of these overhanging portions is brought out, in detail, in the Reichard application, referred to above. 35 Briefly, they make for a more certain cooperation with the car-carried receiver in the train control system in which this inductor is intended to be used.

Referring now to the other figures of the 40 drawings, it will be seen in Fig. 3 that the core C has a generally inverted U-shape inside elevation, with the arms 10 and 11 downwardly inclined to form a bridge effect. From Fig. 3 it is also seen that the neck 9 45 of the core is downwardly bent where it receives the coil 12 in order to position the upper edge of this coil well below the horizontal upper faces of the arms 5-6 etc. In a like manner the laminations are formed with notches in their upper faces, at the points 50 where the coils 13 and 14 are received, whereby to likewise position these coils well below the horizontal plane of the top faces of the arms 5-6 etc. so as to avoid any rubbing or 55 wearing of the coils.

The core and coil structures together with the condensers, as described above, are all snugly received in a casing of wood or other suitable material formed in two sections, 25 and 26, divided longitudinally of the length 60 of the inductor, with the two parts of the casing firmly clamped together by means of bolts or the like 27. The two parts 25 and 26 of the wooden casing have various matching cut-out portions for receiving the core

and coil structure and condensers, all as shown most clearly in Figs. 3-5 inclusive. It is seen that the condensers 18 and 19 are positioned in the wooden casing beneath the parallel arms 7-8 of the core, while the condenser 15 is positioned within the wooden casing underneath the parallel arms 5-6 of the core, to thereby make a rugged and compact structure.

Cut-out portions, as 28, (Fig. 5) are provided for passage of the various wires involved.

After the various parts have been placed in the wooden casing, and the casing securely clamped together, a metal outer casing 29, 80 having a top portion and two side portions, is placed about the whole, and bolted in place as by bolts 30. A junction box, JB, is bolted to the casing 29, at one side thereof, and has an inlet opening 31 for wires connected to terminal posts 32, which wires then pass through an opening 33, in one of the members constituting the wooden casing, to then pass to the various coils and condensers through channels such as 28 provided in the wooden casing. 90

The two parts 25 and 26 of the wooden casing are additionally held in proper position, and protected from the weather, by a non-magnetic metal plate 34 which is inserted in grooves 35 in the members 25 and 26 and then 95 screwed or otherwise fastened to each of these members.

End supports or boots 36 are fastened to the ends of the casing, as by means of bolts 37, and are formed with downwardly inclined 100 ramp faces 38 to aid in preventing any mechanical disturbance of the inductor from its proper position, the boots being connected to ties 39 by screws or the like 40.

The boots 36 and housing 29 are provided 105 with slots 41 for preventing electrical losses due to eddy currents.

In order that the inductor be thoroughly protected against moisture, the inner faces of the metal casing 29 and boots 36 are provided 110 with weather proof and insulating linings.

The wooden casing formed by the members 25 and 26 is thoroughly impregnated, in any usual or desired manner, to protect them against the weather, and all openings between the core and coil and condenser structures and the receiving casing, are filled with suitable compound whereby to make a rigid and weather proof structure.

The above rather specific description of one form of device embodying the present invention, has been given solely by way of illustration, and is not intended, in any manner whatsoever, in a limiting sense. Obviously, this invention can assume many different physical forms, and is susceptible of numerous modifications, and all such forms and modifications are included by this invention, as come within the scope of the appended claims.

Having described my invention, I now claim:—

1. In an inductor for intermittent inductive train control systems, in combination, a laminated core in the general form of an 8, with a central neck interconnecting the loops of the 8, and a projecting arm extending from each loop and in line with the neck, a control coil on each arm and the neck, condensers connected to the various coils, and a longitudinally divided two part casing clamped together and furnished with complementary cut-out portions for receiving the core, coils and condensers.

15 2. In an inductor for intermittent inductive
train control systems, in combination, a lami-
nated core in the general form of an 8, with a
central neck interconnecting the loops of the
8, and a projecting arm extending from each
20 loop and in line with the neck, a control coil
on each arm and on the neck, spacers within
each loop to hold the core portions in looped
position, the neck and arms being taped to
hold the laminæ together, condensers con-
25 nected to the various coils, and a longitudi-
nally divided two part casing clamped to-
gether and furnished with complementary
cut-out portions for receiving the core, coils
and condensers.

30 3. In an inductor for intermittent inductive train control systems, in combination, a laminated core in the general form of an 8, with a central neck interconnecting the loops of the 8, and a projecting arm extending from each 35 loop in line with the neck, a control coil on each arm and the neck, condensers connected to the various coils, and a longitudinally divided two part casing clamped together and furnished with complementary cut-out portions 40 for receiving the core, coils and condensers, the core having its arms downwardly inclined to form an inverted U-shaped core in longitudinal elevation with the condensers positioned with in the U.

45 4. In an inductor for intermittent inductive train control systems, in combination, a laminated core in the general form of an 8 with a central neck interconnecting the loops

of the 8, and a projecting arm extending from each loop and in line with the neck, a control coil on each arm and on the neck, spacers within each loop to hold the core portions in looped position, the neck and arms being taped to hold the laminae together, con-

55 densers connected to the various coils, and a longitudinally divided two part casing clamped together and furnished with complementary cut-out portions for receiving the core, coils and condensers, the core having
60 its arms downwardly inclined to form an inverted U-shaped core in longitudinal elevation with the condensers positioned within the U.

5. In an inductor for intermittent inductive train control systems, in combination, a

laminated core in the general form of an 8, with a central neck interconnecting the loops of the 8 and a projecting arm extending from each loop in line with the neck, a control coil on each arm and on the neck, condensers connected to the various coils, a longitudinally divided two part casing clamped together and furnished with complementary cut-out portions for receiving the core, coils and condensers, the core having its arms downwardly inclined to form an inverted U-shaped core in longitudinal elevation, the condensers being positioned within the U, a non-magnetic metallic casing inclosing the two part casing and its contained parts, and ramp shaped ends on the casing, substantially paralleling said downwardly inclined arms. 70

6. In an inductor for intermittent inductive train control systems, in combination, a laminated core in the general form of an 8 with a central neck interconnecting the loops of the 8 and a projecting arm extending from each loop in line with the neck, a control coil on each arm and on the neck, spacers between the sides of each loop to hold the core portions in looped position, the neck and arms being taped together to hold the laminæ in place, condensers connected to the various coils, a longitudinally divided two part casing clamped together and furnished with complementary cut-out portions for receiving the core, coils and condensers, the core having its arms downwardly inclined to form an inverted U-shaped core in longitudinal elevation with the condensers positioned within the U, a non-magnetic metallic casing enclosing the two-part casing and its contained parts, and ramp shaped ends in the casing substantially paralleling said downwardly inclined arms. 75 80 90 95 100 105

7. In an inductor for intermittent inductive train control systems, in combination, a laminated core in the general form of an **8**, with a central neck interconnecting the loops of the **8** and a projecting arm extending from each loop and in line with the neck, a control coil on each arm and the neck, spacers within each loop to hold the core portions in looped position, the neck and arms being taped to hold the laminæ together, condensers connected to the various coils, a longitudinally divided two part casing clamped together and furnished with complementary cut-out portions for receiving the core, coils and condensers, the core having its arms downwardly inclined to form an inverted **U**-shaped core in longitudinal elevation with the condensers positioned within the **U**, a non-magnetic metallic casing enclosing the two-part casing and its contained parts, and ramp shaped ends on the casing substantially paralleling said downwardly inclined arms, said core, at the points where the coils are carried, being downwardly curved to position the tops of the 110 115 120 125 130

coils well below the top of the core part forming the base of said **U** whereby to provide clearance between coils and metallic casing.

8. In a train control system, a wayside inductor including, in combination, an elongated core, an intermediate and two end coils on the core, a circuit including the two end coils in series, a second circuit including the intermediate coil, traffic controlled means for controlling each of said circuits, and a jumper insertable in position to shunt out the traffic control from the circuit including the two end coils, whereby to choke off the ends of the core regardless of traffic conditions.
15. 9. In a train control system, in combination, a wayside inductor including a core, a plurality of spaced coils on the core, a circuit including one of the coils, a second circuit including another of the coils, traffic controlled means for controlling each of said circuits, and a jumper insertable in position to shunt out the traffic control from the circuit including one of said coils whereby to choke off that portion of the core on which is positioned the shunted out coil regardless of traffic conditions.

In testimony whereof I affix my signature.
PHILIP X. RICE.
